UNITED STATES PATENT OFFICE.

CLARENCE R. SADD, OF ELLINGTON, CONNECTICUT.

CASH-CARRIER.

SPECIFICATION forming part of Letters Patent No. 474,973, dated May 17, 1892.

Application filed March 16, 1891. Serial No. 385,215. (No model.)

To all whom it may concern:

Be it known that I, CLARENCE R. SADD, of Ellington, in the county of Tolland and State of Connecticut, have invented certain new and useful Improvements in Cash-Carriers, of which the following is a full, clear, and exact description, whereby any one skilled in the art can make and use the same.

My invention relates to the class of devices that are used in stores for the purpose of transporting goods or money from the sales table or counter to the cashier's desk; and its object is to provide a simple and compact device of this kind that shall be cheap, simple, and effective, and that shall also use the propelling device as a buffer in stopping the car.

To this end my invention consists in the details of the several parts making up the carriage and propelling device, and in their combination, as more particularly hereinafter described, and pointed out in the claims.

Referring to the drawings, Figure 1 is a detail side view of a part of the apparatus with parts broken away to show construction. Fig. 2 is a detail side view of the same, in section, of the carriage with the parts in position ready to propel the carriage along the way. Fig. 3 is a detail top view of part of the apparatus. Fig. 4 is a detail end view of the same.

In the accompanying drawings, the letter *a* denotes the track or way, preferably a cord or wire, stretched taut between two points and affording a support along which a carriage *b* is adapted to travel. In the form shown the carriage consists of a long tube, fast to which are supports *c* for grooved wheels *d*, that run on the wire that supports the carriage below it. To this tube is fastened any desirable form of removable cash cup or receptacle *e*. The tube contains a coiled spring *f*, preferably provided at opposite ends with disk-like heads *f'*, the ends of the tube being closed with a cap having a perforation *b'*, one of these caps being provided at each end of the tube. The end of the plunger *g* is adapted to enter this opening as the carriage is driven toward it. This plunger *g* is a rod fixed with its axis in the line of the perforation in the cap of the tube in such manner that the plunger will enter the tube when the latter is moved to-

ward it a sufficient distance, and it preferably projects from the front of the frame *h*, that is fixed to a wall or any convenient upright part in proper position to support the device by means of which the carriage is started on a trip.

On the plunger is arranged a sliding collar *i*, and between the back of the collar and the front of the frame is arranged a spring *i'*, that tends normally to hold the collar in a certain position on the plunger. A pin, preferably the end of the screw *i''*, extends through the collar into a groove *g'*, so as to prevent the collar from rotating on the plunger, or the latter may be square and the opening in the collar likewise square, producing the same result. Cords *k* extend from the collar to the drums *k'*, fast to a shaft supported in the frame, and a cord *l*, wound about the drum *k'*, also fast to the same shaft, serves to draw back the collar *i* until the yielding catch *m*, that is borne on the end of the tube, comes in contact with an adjustable stop *a'*, fast to the wire, with the result that the hook *n* of the yielding catch *m* is disengaged from the collar, and by the recoil of the spring *f* the carriage is driven forcibly along the wire. Each end of the tube is provided with a yielding catch, and as the carriage approaches the end of its run the end of the plunger *g* enters the tube and compresses the spring *f*, that acts as an elastic buffer to impede the movement of the carriage. The impetus of the carriage is sufficient to cause the hooked ends of the catch *m* to engage the collar *i*, so as to hold the carriage against recoil. When it is desired to return the carriage to the other end of the way, it is done by pulling down upon the handle fast to the cord *l*, thus drawing the carriage in such manner as to compress the spring *f* between the end of the plunger and the opposite end of the tube, and this compression is continued until the arm *n'* of the yielding catch *m* engages the stop *a'*. A continued pull on the handle causes the hook *n* to be disengaged from the collar and releases the carriage, which is forcibly driven along the way by the recoil of the spring *f*. Each end of the way is provided with the same kind of a detent and releasing device and the opposite ends of the tube are perforated for the

entrance of the plunger at either end, and the spring within the tube is compressible by the entrance of the plunger at either end.

It is evident that my invention does not depend upon the specific form of track or way shown, but that the stopping and propelling means may be embodied in a carriage otherwise supported than in the specific manner shown without departing from my invention, and I do not limit myself to the specific form and arrangement of the several parts shown and described.

I claim as my invention—

1. In a store-service apparatus, in combination with a supporting-way, a wheeled carriage supported on and adapted to travel along said way, the tube forming part of the carriage and provided with openings at each end, the inclosed spring provided at each end with unperforated heads, the plunger adapted to enter the openings in the tube, the sliding collar supported and held against rotation on the plunger and adapted to engage the catch, the means for sliding the collar, and the adjustable trip device, all substantially as described.

2. In a store-service apparatus, in combination with a supporting-way, a carriage adapted to travel along said way, the tube forming part of the carriage, provided at each end with removable caps having openings therethrough, the spring located within the tube, the plunger adapted to enter said tube and to engage the spring, the sliding collar borne on the plunger and held against rotation thereon, the spring tending to hold the collar at the outward limit of its play, the catch device

borne on the carriage and adapted to engage the collar, the adjustable trip device, and the means for sliding the collar, all substantially as described.

3. In a store-service apparatus, in combination with a supporting-way, the wheels *d*, the supports depending from said wheels and bearing the tube, forming part of the carriage, the spring located within the carriage, the plunger adapted to enter the tube and engage the inclosed spring, the sliding collar borne on the plunger, the yielding catch borne on the carriage and adapted to engage the collar, the adjustable trip device, and the means for sliding the collar, all substantially as described.

4. In a store-service apparatus, in combination with a supporting-way, the carriage mounted and adapted to travel thereon, the tube forming part of the carriage, having an opening at each end, the inclosed spring with disk-shaped heads, the receptacle supported on the carriage, the catch device borne on the carriage, the plunger provided with the slot and adapted to enter the opening in the tube, the sliding collar arranged on the plunger and having the screw engaging the slot in the plunger, the spring tending to keep the collar in a certain position, the trip device located in the path of movement of the catch, and the means for sliding the collar, substantially as described.
